UNITED STATES PATENT OFFICE.

FRANK M. WATKINS, OF CINCINNATI, OHIO, ASSIGNOR OF ONE-HALF TO
JOHN T. WEIGHELL, OF SAME PLACE.

DESIGN FOR A FRAME FOR STARCHING-MACHINES.

SPECIFICATION forming part of Design No. 17,105, dated February 8, 1887.

Application filed November 29, 1886. Serial No. 220,214. Term of patent 7 years.

To all whom it may concern:

Be it known that I, FRANK M. WATKINS, a citizen of the United States, residing at Cincinnati, in the county of Hamilton and State 5 of Ohio, have invented and produced a new and original Design for the Frame of a Starching-Machine, of which the following is a specification, reference being had to the accompanying drawing, forming part of said specification, and in which my said design is represented by a perspective view.

My design comprises in its entirety a peculiarly-shaped frame, A. The frame A consists of the following parts, to wit: a flat 15 plinth, 1, of rectangular contour, with rounded corners, from which rises a concave sided stem, 2, of rectangular transverse section, and which, at its upper part, becomes wide from right to left and relatively narrow from front to rear, 20 and terminates at its extreme sides in two vertical columns, 3, which are also of rectangular horizontal section. The top of the stem 2,

midway between the columns 3, has a semi-cylindrical depression, 16, which has a forwardly-extending scoop-shaped projection, 4. 25 The junction of the stem 2 with the two columns 3 is rounded, as at 5.

I claim—

1. The design for the frame of a starching-machine herein shown and described, consisting of the frame A, formed with a plinth, 1, the concave stem 2, the columns 3, and semi-cylindrical depression 16 between the columns. 30

2. The design for the frame of a starching-machine herein shown and described, consisting of the plinth 1, the concave stem 2, the columns 3, and the scoop-shaped projection 4. 35

In testimony of which invention I hereinunto set my hand.

FRANK M. WATKINS.
